(57) **CLAIM**

The ornamental design for an ear curette, as shown and described.

DESCRIPTION

FIG. 1 is a perspective view of an ear curette showing our new design;

FIG. 2 is a right side elevation view thereof;

FIG. 3 is a left side elevation view thereof;

FIG. 4 is a top plan view thereof;

FIG. 5 is a bottom plan view thereof;

FIG. 6 is a rear elevation view thereof; and,

FIG. 7 is a front elevation view thereof.

The broken lines shown in FIGS. 1-5 and FIG. 7 illustrate portions of the ear curette that form no part of the claimed design.

1 Claim, 3 Drawing Sheets
